UNITED STATES PATENT OFFICE.

GEORGE KUSHNER, OF AVELLA, PENNSYLVANIA.

WASHBOILER.

1,363,605.

Specification of Letters Patent. Patented Dec. 28, 1920.

Application filed September 25, 1920. Serial No. 412,627.

To all whom it may concern:

Be it known that I, GEORGE KUSHNER, a citizen of Czechoslovakia, residing at Avella, in the county of Washington, and 5 State of Pennsylvania, have invented certain new and useful Improvements in Wash-boilers, of which the following is a specification.

This invention relates to certain new and 10 useful improvements in wash boilers and has particular reference to the provision of improved means for supporting the clothes above the bottom of the boiler in such manner as to insure efficient boiling of the clothes 15 by aiding in passage of the soapy water to and through the clothes.

Briefly described, the invention resides in the provision of a foraminous or perforated tray for supporting the clothes in spaced 20 relation to the bottom of a boiler, and longitudinally downwardly diverging veins for deflecting the water as it rises when boiled so as to liberate the steam and insure thorough 25 boiling of the clothes, the tray being pivotally mounted so as to tilt laterally under varying steam pressures at opposite sides thereof to further assist in the efficiency of the boiling operation.

With the above general objects in view 30 and others that will become apparent as the nature of the invention is better understood, the same consists in the novel form, combination and arrangement of parts hereinafter more fully described and shown in the accompanying drawings, in which like reference 35 characters indicate similar parts throughout the several views.

In the drawings.

Figure 1 is a substantially central longitudinal vertical sectional view of a wash boiler constructed in accordance with the present invention,

Fig. 2 is a top plan view thereof with the cover removed,

Fig. 3 is a vertical transverse sectional view taken substantially upon line III—III of Fig. 1,

Fig. 4 is a bottom plan view of the clothes supporting tray removed, and

Fig. 5 is a fragmentary detail view showing one of the bearings of the boiler proper which support the tray for lateral tilting movement.

Referring more in detail to the several 55 views, the present invention employs the

usual form of boiler or receptacle 5 having a cover 6 which is removable by use of the handles 7 thereon, the receptacle 5 being also provided with end handles 8 to enable the same to be lifted or carried from place to place as necessary.

Projecting inwardly from the opposite ends of the receptacle 5 are a pair of aligned U-shaped bearings 9 arranged to pivotally receive the end pivot pins 10 rigidly provided on the clothes supporting tray 11 whereby said tray is supported a suitable distance above the bottom of the receptacle 5.

In the preferred embodiment of the invention, the tray 11 is formed of sheet metal 70 with numerous perforations 12 therein for allowing free boiling of the water and passage of the same and steam upwardly through the clothes placed upon the tray. It will, of course, be understood that the tray 75 may be constructed of any foraminous material which will serve the purpose, but the sheet metal form shown is preferred and the main or plate portion of the tray is provided with end depending flanges 13 which act as 80 deflectors and serve to strengthen the tray.

A plurality of downwardly diverging fins 14 are rigid with and depend from the tray 11, said fins being downwardly and outwardly inclined at opposite sides of the longitudinal axis of the tray and being arranged parallel to said axis as well as of gradually decreasing widths from each side to the center for obtaining better results than if the fins were of uniform widths.

In operation, the clothes are placed upon the tray 11 and water is introduced within the receptacle 5 in the usual manner after which the cover 6 is placed on the receptacle 5 and the boiler is then subjected to heat for 95 causing boiling of the water. When the water boils, the same rises and strikes the fins 14 as well as the flanges 13 so as to liberate the steam and to pass with the latter upwardly through the perforations 12 so as 100 to thoroughly permeate the clothes. At times, the steam pressure is greater at one side than the other and thereby causing tilting of the tray for liberating this excessive steam and performing the boiling operation 105 generally in a better way.

In view of the foregoing description, it is believed that the construction and operation of the invention will be readily apparent to those skilled in the art.

Minor changes may be made without departing from the spirit and scope of the invention as claimed.

What is claimed as new is:

- 5 1. In combination with a boiler receptacle having opposed bearings projecting inwardly from the opposite ends thereof, a foraminous tray for supporting clothes above the bottom of said receptacle and having pivot pins journaled in said bearings, whereby a lateral tilting of the tray is permitted upon excessive steam generation at either side of the tray, and longitudinally disposed fins depending from the tray, said fins projecting at an outward incline at opposite sides of the longitudinal center of the tray.
- 10
- 15

2. In combination with a boiler receptacle having opposed bearings projecting inwardly from the opposite ends thereof, a 20 foraminous tray for supporting clothes above the bottom of said receptacle and having pivot pins journaled in said bearings, whereby a lateral tilting of the tray is permitted upon excessive steam generation at 25 either side of the tray, and longitudinally disposed fins depending from the tray, said fins projecting at an outward incline at opposite sides of the longitudinal center of the tray and being of gradually decreasing 30 widths from the sides to the center of said tray.

In testimony whereof I affix my signature.
GEORGE KUSHNER.
